DISPLAY DEVICE

Harold L. Myers, Morristown, N. J.

Application February 14, 1935, Serial No. 6,499

5 Claims. (Cl. 206—79)

My invention relates to devices for displaying articles of merchandise in an attractive manner and more particularly to display devices of the indicated type which include holding sections adapted to removably hold the merchandise in display positions. Experience has shown that in many instances it is desirable to make the aforesaid holding sections of triangular form or arrangement because of the rigidity and other advantages of such holding sections; the rigidity of such triangular holding sections as constructed up to the present however has the disadvantage that it prevents the display device from being folded to a flat condition and accordingly develops difficulties in shipping and storing the display devices of which such triangular holding sections form a part. The object of the invention is to provide a display device of novel construction in which all of the advantages of the aforesaid triangular holding sections are retained and in which in addition said holding sections are readily foldable to a flattened condition which facilitates storing and shipping; the invention contemplates further the provision of a foldable arrangement in which the adjustment of the device from its folded condition to an operative condition automatically adjusts the holding section or sections to an operative peaked position corresponding in efficiency to the triangular holding sections of previous devices. Other objects will appear from the description hereinafter and the features of novelty will be pointed out in the claims.

In the accompanying drawings which illustrate examples of the invention without defining its limits, Fig. 1 is a perspective view of one form of the novel display device in its operative condition; Fig. 2 is a front view of said display device in its folded condition; Fig. 3 is a section on the line 3—3 of Fig. 1; Fig. 4 is a section on the line 4—4 of Fig. 2; Fig. 5 is a fragmentary rear view of the device in its folded condition; Fig. 6 is a view of the blank from which the device shown in Figs. 1 to 5 inclusive is constructed; Fig. 7 is a front view of another form of the device; Fig. 8 is an edge view thereof and Figs. 9 and 10 are edge views of another form of the device showing the same in an operative and a folded condition respectively.

In all of its forms the novel display device consists essentially of a body portion and at least one and preferably two foldable holding sections arranged in spaced parallel relation to each other and of peaked form in their operative positions, 55 in association with foldable means hinged to the

body portions and to the holding section or sections respectively, and adapted to fold said holding sections to a flattened inoperative position and to automatically adjust said holding sections to their operative peaked form.

In the form shown in Figs. 1 to 6 inclusive, the body portion of the display device consists of a main panel 11 and two rear panels 12 which in the illustrated example overlap each other and lie in surface engagement with the rear face of 10 the main panel 11, as shown in Fig. 3; the rear panels 12 are fastened to the main panel 11 in any suitable manner as by means of wire staples or stitches 13. In the form now being described the holding sections 14 extend vertically of the 15 device in spaced parallel relation and, as shown in Fig. 1, each consists of two members hinged together at 15 and having their inner edges hinged to the main panel at 16. The holding sections 14 are provided with any suitable means for 20 receiving and removably holding the articles of merchandise for which the particular display device is designed; in the illustrated example the means referred to is shown in the form of circular openings 17 dimensioned to receive cylindrical 25 articles of merchandise such as indicated at 18 by dotted lines in Fig. 3. As shown in Fig. 3, the rear panels 12 project in opposite directions beyond the main panel 11 to provide projecting portions to which the previously mentioned foldable means is hinged. In the form under discussion this foldable means consists of rear flaps 19 hinged along their inner edges at 20 to the projecting portions of the rear panels 12 and hinged along their outer edges at 21 to front flaps 22 35 which in turn are hinged along their inner edges at 23 to the outer edges of the holding sections 14.

The parts are so designed and dimensioned that in the operative position of the holding sections 14 the hinge 23 is located between the 40 hinges 16 and 23 and preferably in registry with the hinge 15, whereby the two members of each holding section 14 are foldably connected together, or otherwise expressed, in registry with the ridge of the peaked holding section; in the 45 aforesaid operative position of the parts the foldable means occupies a position in which it lies in the plane of the body portion, that is the front flaps 22 lie in the plane of the main panel 11 and the rear flaps 19 correspondingly lie in the plane 50 of the rear panels 12. In this adjustment of the device, the holding sections 14 are accordingly adjusted to peak form with the openings 17 thereof in position to receive the articles of merchandise 18 in the manner indicated in Fig. 3. 55

It will be noted when the articles of merchandise 18 are in position in the holding sections 14 illustrated in Fig. 3 that said articles 18 extend in opposite directions beyond the hinges 20 and accordingly serve to stiffen the device and prevent the parts from folding unintentionally on said hinges 20. To fold the device to a flattened condition, the foldable means, that is the rear flaps 19 thereof are folded rearwardly of said 10 rear panels 12 on the hinges 20 to the position illustrated in Fig. 4. As this rearward folding of the rear flaps 19 takes place, the members of the holding sections 14 are folded on the hinges 16, 15, and 23 respectively, so as to occupy the folded flattened condition shown in Fig. 15 4 in which the two members of each holding section are located upon opposite faces of the device respectively. As the rear flaps 19 are folded forwardly into the plane of the rear panels, the front flaps 22 20 will be likewise folded forwardly into the plane of the main panel 11 and will automatically adjust the holding sections 14 to the operative peak form shown in Figs. 1 and 3. This is due to the fact that the dimensions of the 25 two members of each holding sections 14 between the hinges 16 and 15, and 15 and 23, and of the front flaps 22 between the hinges 23 and 21 are greater than the dimensions of the rear flaps 19 between the hinges 20 and 21. Any suitable 30 means may be included in the device for supporting the same in operative position; in the form now being described this means comprises an extension 24 of the main panel 11.

In the form shown in Figs. 7 and 8 the holding 35 sections 14^a corresponding to the holding sections 14 of the form first described, extend in horizontal parallel relation to each other and are hinged along their inner edges at 16^a to the main panel 11^a and along their outer edges at 23^a 40 to the front flaps 22^a of the foldable means. These front flaps are hinged at 21^a to the rear flaps 19^a which, as in the first form, have their inner edges hinged at 20^a to the projecting portions of the rear panels 12^a. The latter as in 45 the form first described are located in surface engagement with the rear face of the main panel 11^a and are secured in place in any convenient manner as by wire staples or stitches 13^a. In the form now being described the foldable means at 50 the upper end of the device may constitute the means whereby the device may be suspended in display position and for this reason is of somewhat increased dimensions. Because of this and to add to the rigidity of the display device fastening devices such as wire staples or stitching 55 25 may be located at intervals in registry with the hinge 23^a for the purpose of fastening the front flaps 22^a and the rear flaps 19^a together on said hinge 23^a at said upper end of the device.

This form of the device is foldable in the same manner as described with respect to the first form; that is, by folding the front flaps 22^a and the rear flaps 19^a rearwardly on the hinges 23^a, the holding sections 14^a will be folded to a flattened inoperative condition in the same way as previously described. When the flaps 22^a and 65 19^a are folded forwardly in the manner set forth with respect to the flaps 22 and 19, the holding sections 14^a will be automatically adjusted to their operative peaked form in the same way as previously described.

In the form shown in Figs. 9 and 10, flaps corresponding to the front flaps 22 or 22^a have been done away with and the rear flaps have been replaced by corresponding flaps 19^b of reduced di-

75 mensions and hinged directly along their outer edges to the outer edges of the holding sections 14^b, as indicated at 23^b in Fig. 9; the flaps 19^b are hinged along their inner edges at 20^b to the projecting portions of the rear panels 12^b in the same way as in the other illustrated forms of the device. Otherwise, the form now under discussion may be the same as either of the two forms previously described and is adjustable to fold the holding sections to a flattened condition and to the peaked 10 operative condition in the same way as in the two other forms illustrated in the drawings. It will be understood that in the two forms shown in Figs. 7 to 10, the arrangements are such that the hinges 20^a and 20^b, in the operative condition of 15 the device, are located in registry with the hinges whereby the two members of each holding section are hinged together; in other words, in all of the forms of the device the hinges 20, 23^a, and 20^b are located in registry with the ridges of the holding 20 sections when the latter occupy their peaked operative form.

In the illustrated examples the hinges referred to in the description are shown in the form of score lines which is the simplest way of producing 25 the desired results; it is to be understood however that such score lines are not intended to arbitrarily indicate the only form of hinge which may be utilized in the construction of the device in all of its forms. It is further to be understood that 30 the openings 17 may be replaced by other types and forms of means for receiving and removably holding the articles of merchandise, the character of such holding means being dependent upon the 35 nature of the articles of merchandise for which the device, in each instance, is designed.

The novel device involves no difficulty in its construction and as is evident retains all of the advantages inherent in the triangular form of holding sections and at the same time includes 40 the essential additional advantage that the device as a whole is foldable to a flattened compact condition whereby storage and shipping is greatly facilitated.

Various changes in the specific forms shown 45 and described may be made within the scope of the claims without departing from the spirit of the invention.

I claim:

1. A display device comprising a main panel, 50 a pair of rear panels lying in surface engagement with the rear face of said main panel and secured thereto, said rear panels projecting beyond opposite edges of said main panel, foldable holding sections hinged along their inner edges to said 55 opposite edges of the main panel and of peaked form in their operative positions, rear flaps hinged along their inner edges to the projecting portions of said rear panels, and front flaps hinged to the outer edges of said rear flaps and to the outer 60 edges of said holding sections, said rear flaps being foldable rearwardly of said rear panels to fold said holding sections to flattened inoperative positions and forwardly into the plane of said rear panels to automatically adjust said holding 65 sections to operative peaked form.

2. A display device comprising a main panel, a pair of rear panels lying in surface engagement with the rear face of said main panel and secured thereto, said rear panels projecting beyond opposite edges of said main panel, foldable holding sections hinged along their inner edges to said 70 opposite edges of the main panel and of peaked form in their operative positions, and rear flaps hinged along their inner edges to the projecting 75

5 portions of said rear panels and foldably connected with the outer edges of said holding sections, said rear flaps being foldable rearwardly of said rear panels to fold said holding sections to flattened, inoperative positions and forwardly into the plane of said rear panels to automatically adjust said holding sections to operative peaked form.

10 3. A display device comprising a main panel, a pair of rear panels lying in surface engagement with the rear face of said main panel and secured thereto, said rear panels projecting beyond opposite edges of said main panel, foldable holding sections hinged along their inner edges to said 15 opposite edges of the main panel and of peaked form in their operative positions, and rear flaps hinged along their inner edges to the projecting portions of said rear panels and having their outer edges hinged directly to the outer edges of said holding sections, said rear flaps being foldable rearwardly of said rear panels to fold said holding sections to flattened inoperative positions and forwardly into the plane of said rear panels to automatically adjust said holding sections to operative peaked form.

20 25 4. A display device comprising a main panel, a pair of rear panels lying in surface engagement with the rear face of said main panel and secured

thereto, said rear panels projecting beyond opposite edges of said main panel, foldable holding sections hinged along their inner edges to said opposite edges of the main panel and of peaked form in their operative positions with their ridges in registry with the outer edges of said rear panels, and means foldably connected with said outer edges of said rear panels and with the outer edges of said holding sections, said means being foldable relatively to said rear panels to fold said holding sections to flattened inoperative positions and to automatically adjust said holding sections to operative peaked form respectively. 5

5. A display device comprising a body portion, a foldable holding section hinged to said body 15 portion and of peaked form in its operative position, and foldable means hinged to said body portion and to said holding section, the hinge connecting said means with said body portion being located between the hinges whereby said holding section is connected with said body portion and means respectively and lying in registry with the ridge of said holding section is in its peaked operative position, said means being foldable to fold the said holding section to a flattened inoperative position and to its operative peaked form 20 25 respectively.

HAROLD L. MYERS.
